UNITED STATES PATENT OFFICE.

RAYMOND L. BARTON, OF LOS ANGELES, CALIFORNIA.

DESIGN FOR A COMBINATION SIGNAL CASING.

Application filed March 23, 1927. Serial No. 21,286. Term of patent 3½ years.

To all whom it may concern:

Be it known that I, RAYMOND L. BARTON, a citizen of the United States, residing at Los Angeles, in the county of Los Angeles and State of California, have invented a new, original, and ornamental Design for a Combination Signal Casing, of which the following is a specification, reference being had to the accompanying drawing, forming part thereof.

Figure 1 is a front elevation, and Figure 2 is a side elevation, showing my new design.

I claim:

The ornamental design for a combination signal casing, substantially as shown.

RAYMOND L. BARTON.
